UNITED STATES PATENT OFFICE

HENRY T. SAFFORD, SR., OF EL PASO, TEXAS

DEVICE FOR PRESSING SOAP

Application filed August 27, 1929. Serial No. 388,763.

This invention relates to pressing devices and pertains particularly to a soap press.

The primary object of this invention is to provide a device by means of which odd pieces of soap may be firmly pressed into a cake of sufficient size and proper form to provide a cake, thus making it possible to completely use up all of the bits of soap cakes commonly found about households.

10 The invention broadly contemplates the provision of a box or casing preferably of cylindrical formation and open at each end, with a cap threadably engaged over each end and having a threaded shaft extending 15 through the center of one of the caps and carrying a follower which is moved longitudinally in the box by rotation of the shaft. Soap chips placed in the box will thus be pressed firmly against the cap upon the opposite end thereof to compress the chips into a cake. Removal of the cake is effected by removing the cap against which the cake is formed and then rotating the follower slightly to force the cake from the box.

20 25 The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications 30 mark no material departure from the salient 35 features of the invention as expressed in the appended claim.

In the drawing:—

Figure 1 is a view in side elevation of the soap press embodying the present invention. 40 Figure 2 is a longitudinal sectional view taken upon the line 2—2 of Figure 1.

Figure 3 is a transverse sectional view taken upon the line 3—3 of Figure 2.

Referring more particularly to the drawing, the numeral 1 indicates generally the casing of the soap presser embodying the present invention, the same being preferably of cylindrical formation, as shown. Each end of the casing or box in which the soap cake 45 is formed is exteriorly threaded as indicated

at 2 to receive the caps 3 and 4 which close the top and bottom ends of the box respectively. The inner wall of the box is provided with a plurality of longitudinally extending grooves 5 which act to prevent the soap cake 55 from rotating while being pressed down by the plunger or follower 6 which snugly fits into the box.

This follower is carried upon the inner end of a threaded shaft 7 which passes 60 through and has threaded engagement with an aperture 8 formed in the center of the top cap 3, as shown. The outer end of the shaft 7 carries the laterally extending arms 9 by means of which rotation of the shaft is 65 facilitated, these arms being of substantial length so that creation of a high pressure may be brought about to firmly compress soap chips in the box.

In the use of the present soap cake press 70 the odd ends of soap cakes are collected and broken up into small pieces and then sterilized by immersion in hot water for a period of from three to five minutes after which they are placed in the box and the caps or 75 covers secured in position.

The shaft 7 is then rotated to force the soap chips firmly against the bottom cap 4. The device is then allowed to remain with the soap under pressure for a period of several hours after which the cake will have become set and will be found firm and ready 80 for use upon removal.

By providing the inner face of the wall of the cylinder or casing 1 with the longitudinally extending grooves 5 the soap cake after it is formed by the rotating follower is prevented from turning and is also ejected straight from the cylinder after the cap 4 has been removed and the follower pressed 85 against the cake.

Having thus described my invention, what I claim is:—

A soap press of the character described comprising a cylindrical casing open at each 90 end, a cap threadably engaging over and closing each end of the casing, one of said caps having a threaded aperture through the center thereof, a follower designed to snugly 95 position in the casing to reciprocate therein, 100

a threaded shaft attached at one end to said follower and extending through and engaging in the threaded aperture, and lateral arms carried by said shaft at its outer end to facilitate its rotation, said casing having the inner face of the wall provided with a series of longitudinally extending grooves extending throughout from one end to the other.

5 In testimony whereof I hereunto affix my
10 signature.

HENRY T. SAFFORD, Sr.
